Primary Examiner — Jack Reickel*Assistant Examiner* — Salamah Jordan(74) *Attorney, Agent, or Firm* — Procopio, Cory, Hargreaves & Savitch LLP(57) **CLAIM**

The ornamental design for a seated treadmill, as shown and described.

DESCRIPTION

FIG. 1 is a left perspective view of our seated treadmill;

FIG. 2 is the front perspective view thereof;

FIG. 3 is the left perspective view thereof;

FIG. 4 is the rear perspective view thereof;

FIG. 5 is the right perspective view thereof; and,

FIG. 6 is the top perspective view thereof.

Note: The broken lines in the drawings depict portions of the seated treadmill that form no part of the claimed design.
